GLOW DISCHARGE RECTIFIER WITH
HOLLOW CATHODES

Johannes Nienhold, Berlin-Charlottenburg, Germany, assignor to Siemens & Halske Aktiengesellschaft, Siemensstadt, near Berlin, Germany, a Corporation of Germany

Application December 16, 1932, Serial No. 647,553,
and in Germany August 27, 1931

1 Claim. (Cl. 250—27.5)

This invention relates to glow discharge rectifiers with hollow cathodes.

The method of constructing glow discharge rectifiers in such a manner that two, preferably point-shaped anodes project into a hollow space serving as a cathode is well-known in the art. It is also well known that the hollow space can be given the shape of a tube into the two ends of which the anodes project. It is furthermore well known that a direct discharge between the two anodes can be prevented by placing between them one or several screens preventing a direct passage between the anodes. The drawbacks of such rectifiers consist more particularly in that the cathode fall (the potential drop between the cathode and the anodes) is relatively high and, consequently the efficiency of the rectifier is very low.

According to the invention, a glow discharge rectifier having at least two anodes and a subdivided hollow cathode carrying a layer which increases electron emission is constructed so as to enable two or several anodes to project into a hollow cathode system completely closed outwardly from a discharge-operative standpoint, in such a manner that a discharge between them would only be possible through the hollow cathode interstices, however, the distance between the cathode surfaces being, however, chosen so as to prevent lines of force from being developed between the anodes.

A hollow cathode is understood to be a subdivided cathode in which the different parts are arranged in such a manner and at such a distance apart that the electrons liberated from one portion of the cathode by the impingement of positive ions are propelled into the cathode fall space (region surrounding the cathode in which the potential drop occurs) at the opposite portion of said cathode and are stopped in this fall space, thus giving rise to a concentration of electrons in the hollow spaces of the cathode and, consequently, to a reduction of the cathode fall or voltage drop between the anodes and cathode.

Such hollow cathodes and the principle of constructing them are already known in the art for a long time past. Mention will therefore only be made of the following conditions: The distances separating the opposite hollow cathode surfaces must be in a definite ratio to the filling gas and its pressure, i. e. the distances should be less than or equal to the fall space thickness at a cold simple cathode under corresponding conditions. So far as they cannot be determined by experiments, these distances may be roughly

calculated by making them equal to ten times or twenty times the length of the mean free gas-kinetic electron path. The electron path length l within a gas or vapour of a pressure of p millimeters is:

$$l = \frac{4300}{p} l_0$$

where l_0 is the mean free path of a neutral gaseous molecule, which may be found in chemical tables. For mercury vapour, helium, argon and neon, the values for the electron path length in millimeters for a pressure p of 1 mm. are as follows:

Hg	Ar	Ne	He
0.093	0.29	0.54	0.77

A multiplication of these values by from 10 to 20 results in the approximate fall space thickness at a gas pressure of 1 mm.

Figs. 1 and 2 show examples constructed according to the invention:

Fig. 1 shows an electrode system for a rectifier embodying the invention. The two anodes 1 and 2 project into a completely closed hollow cathode system 3. The two leads for the anodes 1 and 2 are shielded from glow discharge by means of insulating tubes 4 and 5. The hollow cathode system itself consists of a metal envelope 6 in which there are located superposed metal sheets 7, 8, 9 and 10. The distance separating these sheets and the pressure of the filling gas have been chosen in such a manner that direct electrostatic lines of force cannot be developed between the two anodes 1 and 2, and, consequently, a discharge between the anodes cannot take place.

Another constructional example is shown in Fig. 2. Within in a discharge vessel 11, there are located two re-entrant portions 12 and 13, carrying the anodes 14 and 15 which are protected from glow discharge by insulating tubes 16 and 17. The two anodes 14 and 15 project into a completely closed cylindrical hollow cathode system 18. The direct connection between 14 and 15 is interrupted by concentrically arranged tubular sheets 19, 20 and 21, so that direct lines of force cannot be developed between 14 and 15. The lead to the hollow cathode system is introduced at 22.

The surfaces of the cathode metals can be made of increased electron emissivity in a manner well-known in the art, for instance by means

of barium films on an oxide which have been obtained from barium azide, BaN₂. In filling these tubes, use should preferably be made of rare gases.

5 I claim as my invention:

A rectifier of the glow discharge type comprising an evacuated envelope containing a rarified atmosphere, a plurality of anodes, a hollow cathode, conductive means forming part of said cath-

ode and positioned therein subdividing the hollow space between the anodes within the cathode into a plurality of interstices, the width of said interstices being substantially small enough to prevent the direct passage of electrostatic lines of force between said anodes at the pressure conditions prevailing within said envelope. 80
